ULTRA-HIGH-FREQUENCY SIGNAL-TRANSLATING STAGE

William H. Aldous, Wembley, England, assignor to Hazeltine Corporation, a corporation of Delaware

Application September 25, 1940, Serial No. 358,223
In Great Britain November 7, 1939

5 Claims. (Cl. 179—171)

This invention relates to ultra-high-frequency signal-translating stages for operation at such high frequencies that conductance of the input circuit of the stage is an appreciable factor in determining the response of the stage.

The present invention is an improvement of the invention disclosed and claimed in the co-pending application of Harold A. Wheeler, Serial No. 277,862, filed June 7, 1939, now United States Letters Patent No. 2,279,543, issued April 14, 1942, and assigned to the same assignee as the present application.

The input conductance of conventional vacuum tubes employed in ultra-high-frequency signal-translating stages, such as ultra-high-frequency amplifiers, tends materially to reduce the response of the stage. At frequencies above 10 megacycles or thereabout, the input conductance of conventional vacuum tubes is appreciable, while at frequencies higher than 50 megacycles, the input conductance, rather than the inherent tube and circuit capacitance, becomes the limiting factor in the response of the stage. The reason for this condition is that the maximum impedance which can be developed across the input circuit of the stage, which determines the effective coupling to the preceding stage, at such ultra-high frequency is limited by the input conductance of the tube.

Also, at ultra-high frequencies, the input capacitance of such a stage and the variation of input capacitance with variations of the transconductance of the vacuum tube employed are both appreciable, thereby adding other limitations to the response of the system. While there have been proposed arrangements for reducing the input capacitance of a vacuum tube and for maintaining it substantially uniform with variations of the transconductance of the tube when utilized in such an ultra-high-frequency stage, such arrangements in themselves have not been effective to compensate for the conductance of the input circuit and some arrangements for stabilizing the input capacitance have even introduced appreciable additional conductance into the input circuit. Arrangements have been proposed for effectively reducing to a low value the conductance of the input circuit of the stage. Such arrangements have generally been satisfactory where the anode load of the tube employed has a very small impedance at the frequency of the signals translated by the stage but anode loads of large impedance at the signal frequency tend to reduce somewhat the compensation effected, since the anode potential may vary greatly during each cycle of the translated signal.

It is an object of the present invention, therefore, to provide an improved ultra-high-frequency translating stage which is not subject to

the above-mentioned disadvantages and limitations of the arrangements of the prior art.

It is a further object of the invention to provide an improved ultra-high-frequency signal-translating stage having a response which is not materially limited by the conductance of the input circuit nor the value of the load impedance in the output circuit of the vacuum tube included in the stage.

10 In accordance with the invention, an ultra-high-frequency signal-translating stage comprises a vacuum tube having a cathode, an anode, and a control electrode, and includes an input circuit coupled to said cathode and said control electrode and an output circuit coupled to said anode and said cathode, the stage having incidental reaction to the input circuit tending to develop substantial conductance thereacross under normal operating conditions. The vacuum tube includes an auxiliary anode having appreciable capacitance with said control electrode and a screen electrode between the anodes to reduce capacitive currents therebetween. The signal-translating stage is provided with a circuit coupled to the auxiliary anode and to the cathode including inductance, and means for applying a unidirectional positive potential to the auxiliary anode, the inductance being of such value with respect to said capacitance as effectively to neutralize a substantial part of the conductance of the input circuit.

For a better understanding of the present invention, together with other and further objects thereof, reference is had to the following description taken in connection with the accompanying drawing, and its scope will be pointed out in the appended claims.

It is well known that one of the factors limiting the repeating ratio of signal amplifiers including 40 a conventional vacuum tube is the inherent inductance of the cathode lead which is common to the input and output circuits of the amplifier, the presence of this inductance having a degenerative effect in the input circuit simulating an input conductance. The input conductance, due to the inherent cathode inductance is:

$$Vi - \omega^2(S_a + S_s) L_K C_{Kc} \quad (1)$$

where,

$\omega = 2\pi$ times the signal frequency;

50 S_a =the mutual conductance from control grid to anode of the tube employed;

S_s =the mutual conductance from control grid to accelerating or screen grid; and

55 C_{Kc} =the effective capacitance between the cathode and control grid.

As taught by the aforementioned Wheeler application, if an inductor L_s is positioned in the circuit of the accelerating or screen grid, it pro-

duces in the input circuit an apparent input conductance:

$$V' = -\omega^2 S_a L_a C_{sc} \quad (2)$$

where C_{sc} is the capacitance between the control and screen grids. Accordingly, the effect of inherent inductance L_K of the cathode lead can be compensated by placing in the screen-grid circuit an inductor L_s having a value:

$$L_s = \frac{L_K (S_a + S_s)}{S_s} \frac{C_{KC}}{C_{sc}} \quad (3)$$

The reason for this is, very briefly, that the potential of the screen grid due to the potential drop across the screen-grid inductor L_s is equal and opposite to the potential produced on the control grid by potential variations of the cathode due to the inherent cathode inductance L_K and applied to the control grid through the control grid-cathode capacitance C_{KC} .

This method of compensation is effective in oscillator-modulators or frequency changers in which the anode load impedance has usually a relatively small value at the frequency of the input signal. In signal-translating stages such as signal amplifiers, however, the anode load impedance necessarily has a large value at the signal frequency. This causes variations of anode potential occurring during normal operation to be fed back to the screen grid through the anode screen-grid capacitance C_{AS} , thereby causing corresponding variations in a potential of the screen grid which may detrimentally affect the compensation of the input conductance.

Referring now to the single figure of the drawing, there is represented a circuit diagram of a stage of ultra-high-frequency amplification embodying the invention. This stage comprises a vacuum-tube amplifier 11 having an input circuit including an inductor 12 tuned by capacitance 10. The tube 11 is provided with a cathode 2 and a control grid or electrode 3; which are connected to the input circuit, and has an anode 5 and cathode 2 connected in an output circuit having a high anode-load impedance and including an inductor 13 tuned by a condenser 14 to the frequency of the signal to be translated. The tube 11 additionally is provided with an auxiliary anode or additional electrode 1 and a screen grid or electrode 4 which are connected externally of the tube through an inductor L_A and energized together through a resistor 15 from a source of unidirectional potential $+S_c$. The additional electrode 1 is positioned to receive, under the control of the control grid 3, electrons emitted from the cathode 2. The stage has appreciable capacitance between the auxiliary anode 1 and the control electrode 3 which is represented by the dotted-line condenser C_{AC} . The screen grid 4 is returned to ground for currents of signal frequency by a by-pass condenser 16. Tube 11 has a suppressor grid 17 connected directly to the cathode 2. The cathode circuit has an inherent lead inductance represented in lumped form by the inductor L_K which is the portion common to both the input and output circuits of the amplifier stage. The inherent capacitance between the control grid 3 and cathode 2 is represented by the condenser C_{KC} .

In considering the operation of the signal-translating stage just described, ultra-high-frequency carrier signals applied to the input circuit of the stage are translated by tube 11 and appear in amplified form in the output circuit of the stage. The signal-translating stage has an

incidental reaction to the input circuit tending to develop substantial conductance thereacross under normal operating conditions which is effectively simulated by the inductance L_K in the common portion of the input and output circuits. The inductance L_A which is employed is of such a value with respect to the capacitance C_{AC} between the auxiliary anode 1 and the control electrode 3 as to neutralize effectively a substantial part of the conductance of the input circuit; or, stating it differently, the inductance L_A is so proportioned with respect to the simulated inductance that the voltage developed across the inductance L_A and coupled to the input circuit through the capacitance C_{AC} effectively neutralizes a substantial part of the conductance in the input circuit. The inherent inductance L_K of the cathode circuit is common to the input and output circuits and, therefore, has a degenerative effect in the input circuit. However, it will be seen that negative conductance is introduced into the input circuit of the stage due to the voltage developed across the inductor L_A and fed back to the input circuit through the auxiliary anode-control grid capacitance C_{AC} whereby the positive conductance of the input circuit produced by the inherent cathode inductance L_K is wholly or partially compensated by the negative conductance effect of the inductor L_A . In order to produce exact compensation, the value of the inductor L_A is proportioned in accordance with the following equation derived by analogy to Equation 3:

$$L_A = L_K \frac{S_a' + S_A \cdot C_{KC}}{S_A \cdot C_{AC}} \quad (4)$$

where,
 S_a = the combined mutual conductance from control grid to anode and screen grid; and
 S_A = the mutual conductance from control grid to the auxiliary anode.

In this operation, it will be observed that the screen grid 4 is at ground potential for currents of signal frequency and its potential, therefore, is fixed regardless of any variations of potential of the anode 5. During operation of the amplifier stage, the screen grid 4 thus electrostatically shields the auxiliary anode 1 from the main anode 5, thereby reducing capacitive currents therebetween, and the potential of the auxiliary anode, therefore, varies only in accordance with the potential drop developed across the inductor L_A and independently of the potential of the anode 5. Thus, the compensation of the input conductance is in no manner detrimentally affected by the anode potential variations as determined by the value of the load impedance in the output circuit of the vacuum tube. The suppressor grid 17 aids the screen grid 4 in electrostatically shielding the auxiliary anode 1 from the main anode 5.

The inductor L_A may be either inside or outside of tube 11 and at ultra-high frequencies, as at frequencies of 10 megacycles or more, may be a straight piece of wire having a length of a few centimeters. Accordingly, if the cathode extends away from the tube seal and the auxiliary anode is placed at the end of the cathode remote from the seal, the lead from the auxiliary anode to the exterior of the tube through the seal may serve as the inductor L_A . However, in order that the capacitance between the auxiliary anode and its lead, on the one hand, and the other electrodes of the tube and their leads, on the other hand, may be small, it may be desirable to bring

the leads to the control grid and auxiliary anode out at one end of the tube envelope and the leads to the other tube electrodes out at the other end of the envelope. In this event, the inductor L_A is preferably positioned externally of the tube.

In order that shot noise may be not materially increased by the current drawn by the auxiliary anode, it is desirable that the current drawn by the main and auxiliary anodes be completely separated, as by providing separate bands of electron-emissive material on the cathode.

The present invention has particular utility in signal-translating stages employing a vacuum tube of the type wherein the mutual conductance between the control grid and screen grid is reduced to a small value by the provision of a guiding grid, the function of which is to prevent current flowing to the screen grid. It is evident from Equation 3 that, if the control-screen-grid conductance S_{ss} is small, an inductor placed in the screen-grid circuit in accordance with prior teachings must be so large that it may be impractical.

It may be observed that the value of the inductor L_A need not necessarily provide exact compensation of the input conductance but may over-compensate to reduce the input conductance component of the stage caused by the finite transit time of the electrons. The transit time effect causes an input conductance that varies similarly with frequency and transconductance to that component caused by cathode lead inductance and evaluated by Equation 1. Thus, the effects, both of transit time and cathode lead inductance, can be either exactly compensated or over-compensated by suitable selection of the value of L_A in accordance with the invention.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An ultra-high-frequency signal-translating stage comprising, a vacuum tube having a cathode, an anode, and a control electrode, an input circuit coupled to said cathode and said control electrode, an output circuit coupled to said anode and said cathode, said stage having incidental reaction to said input circuit tending to develop substantial conductance thereacross under normal operating conditions, an auxiliary anode in said vacuum tube, said stage having appreciable capacitance between said auxiliary anode and said control electrode, a screen electrode between said anodes to reduce capacitive currents therebetween, a circuit coupled to said auxiliary anode and said cathode including inductance, and means for applying a unidirectional positive potential to said auxiliary anode, said inductance being of such value with respect to said capacitance as effectively to neutralize a substantial part of said conductance of said input circuit.

2. An ultra-high-frequency signal-translating stage comprising, a vacuum tube having a cathode, an anode, and a control electrode, an input circuit coupled to said cathode and said control electrode, an output circuit coupled to said anode and said cathode and including a portion common to said input circuit, said stage having in-

cidental reaction to said input circuit tending to develop substantial conductance thereacross under normal operating conditions of said stage which is effectively simulated by an inductance 5 in said common portion of said input and output circuits, an auxiliary anode in said vacuum tube, said stage having appreciable capacitance between said control electrode and said auxiliary anode, a screen electrode between said anodes to reduce capacitive currents therebetween, a circuit coupled to said auxiliary anode and said cathode and including inductance, and means for applying a unidirectional positive potential to said auxiliary anode, said inductance being 10 so proportioned with respect to said simulated inductance that the voltage developed across said inductance and coupled to said input circuit through said capacitance effectively neutralizes a substantial part of said conductance in said input circuit.

3. An ultra-high-frequency signal-translating stage comprising, a vacuum tube having a cathode, an anode, and a control electrode, an input circuit coupled to said cathode and said control electrode, an output circuit coupled to said anode and said cathode, said stage having incidental reaction to said input circuit tending to develop substantial conductance thereacross under normal operating conditions, an additional electrode 15 positioned to receive under control of said control electrode electrons emitted from said cathode, said stage having appreciable capacitance between said control electrode and said additional electrode, means for electrostatically shielding said additional electrode from said anode, a circuit coupled to said additional electrode and said cathode including inductance, and means for applying a unidirectional positive potential to said additional electrode, said inductance being 20 of such value with respect to said capacitance as effectively to neutralize a substantial part of said conductance of said input circuit.

4. An ultra-high-frequency signal-translating stage comprising, a vacuum tube having a cathode, an anode, and a control electrode, an input circuit coupled to said cathode and said control electrode, an output circuit including a high anode load impedance coupled to said anode and said cathode, said stage having incidental reaction to said input circuit tending to develop substantial conductance thereacross under normal operating conditions, an auxiliary anode in said vacuum tube, said stage having appreciable capacitance between said auxiliary anode and 25 said control electrode, a screen electrode between said anodes to reduce capacitive currents therebetween, a circuit coupled to said auxiliary anode and said cathode including inductance, and means for applying a unidirectional positive potential to said auxiliary anode, said inductance being of such value with respect to said capacitance as effectively to neutralize a substantial part of said conductance of said input circuit.

5. An ultra-high-frequency signal-translating stage comprising, a vacuum tube having a cathode, an anode, an auxiliary anode, a screen electrode positioned between said anodes to reduce the capacitive currents therebetween, and a control electrode, an input circuit coupled to said cathode and said control electrode, an output circuit coupled to said anode and said cathode and including a cathode lead common to said input circuit, said stage having combined mutual conductance S_{sa} between said control electrode and said anode and screen electrode and having

incidental reaction to said input circuit tending to develop substantial conductance thereacross under normal operating conditions of said stage, which is effectively simulated by an inductance L_K in said cathode lead common to said input and output circuits, said stage having appreciable capacitance C_{AC} and mutual conductance S_A between said control electrode and said auxiliary anode, a circuit coupled to said auxiliary anode and said cathode and including induct-

10
5
ance L_A , and means for applying a unidirectional positive potential to said auxiliary anode, said inductance being proportioned in accordance with the expression

$$L_A = L_K \cdot \frac{S_{a'} + S_A}{S_A} \cdot \frac{C_{KC}}{C_{AC}}$$

where C_{KC} is the capacitance between said grid and said cathode.
